(57) **CLAIM**

The ornamental design for a D ring as shown and described.

DESCRIPTION

FIG. 1 is a perspective view of a D ring;

FIG. 2 is a front view of the D ring;

FIG. 3 is a rear view of the D ring;

FIG. 4 is a top view of the D ring;

FIG. 5 is a bottom view of the D ring;

FIG. 6 is a left-side view of the D ring;

FIG. 7 is a right-side view of the D ring; and,

FIG. 8 is a perspective view of the D ring shown within its environment.

The broken lines depict the portions of the D ring that form no part of the claimed design. The additional broken lines in FIG. 8 depict environmental subject matter that forms no part of the claimed design.

1 Claim, 8 Drawing Sheets
